UNITED STATES PATENT OFFICE.

DAISY M. BARTEAU, OF CORONADO, CALIFORNIA.

WAVE-MOTOR.

991,265.

Specification of Letters Patent.

Patented May 2, 1911.

Application filed November 15, 1910. Serial No. 592,530.

To all whom it may concern:

Be it known that I, DAISY M. BARTEAU, a citizen of the United States of America, residing at Coronado, in the county of San 5 Diego and State of California, have invented certain new and useful Improvements in Wave-Motors, of which the following is a specification.

This invention relates to wave motors and 10 has for its object the provision of a device constructed in such manner as to convert the uneven and intermittent movement of a float actuated by the ocean's waves into continuous rotary movement of a power shaft, in 15 one direction.

The foregoing object is accomplished by 20 means of a structure in which both the vertical and sidewise movements of the float are utilized as will be hereinafter set forth.

20 Further objects and advantages of the invention will be set forth in the detailed description which now follows:

In the accompanying drawings, Figure 1 is a plan view of a wave motor constructed 25 in accordance with the invention, Fig. 2 is a detail perspective view of the upper portion of a float showing a housing carried thereon, Fig. 3 is a sectional view upon line $x-x$ of Fig. 1, looking in the direction of 30 the arrow "a," Fig. 4 is a sectional view upon line $x-x$ of Fig. 1, looking in the direction of the arrow "b," Fig. 5 is a detail view illustrating a connection between a swinging arm and a chain hereinafter described, Fig. 35 6 is a detail perspective view of the connections between the arms of a power lever, hereinafter described, and the members actuated thereby, Fig. 7 is a detail view illustrating a sliding rod which acts to impart 40 the movement of the float to said power lever, Fig. 8 is a detail sectional view through one of the cross-arms carried by said sliding rod, Fig. 9 is a partial end elevation of the float showing said cross-arms 45 and the housing on the float, Fig. 10 is a detail view of a latch for securing a swinging closure which normally closes one side of said housing, Fig. 11 is a detail view of one of the guides employed in connection 50 with a toothed segment hereinafter described, and Figs. 12, 13, 14, and 15 are detail views of the pawl and ratchet connections hereinafter described, upon lines 4-4; 2-2; 3-3; and 1-1 of Fig. 1, respectively,

and Fig. 16 is a sectional view upon line 55 16-16 of Fig. 7.

Like numerals designate corresponding parts in all of the figures of the drawings.

Referring to the drawings, the numeral 5 designates a pier supported upon posts or 60 piles 6. Located adjacent this pier, is a float 7. Anchor posts 8, 9, and 10 are located at suitable distances from the float and anchor chains 11, 12, and 13 lead from these posts to the float. Mounted upon the top of the 65 float is a housing 14, open at each end and having one of its sides normally closed by a hinged closure 15. A latch 16 normally holds this closure shut.

A rod 17 is slidably disposed in the tubular portion 18 of a power lever and carries 70 a head 19 which limits the outward movement of said rod, to prevent the possibility of said rod working out of said lever. Upon its outer end (see Figs. 2 and 9), the rod 17 75 carries a spider 20. Housings 21 upon the ends of the arms of this spider receive anti-friction balls 22 adapted to contact with the sides of the housing 14 of the float.

The head 19 is preferably oval as also is 80 the tubular portion of power lever 18 (see Fig. 16) to prevent the rod 17 from turning and to consequently hold said spider in the proper position for the balls 22 to contact with the top, bottom, or sides of the housing 85 14, as will be readily understood.

Preferably the open end of the housing 14 next to the pier is slightly larger than the outer end thereof. Arms 24 and 25 are rigid 90 with and extend from the inner end of the tubular member 18. The arm 24 terminates in a vertical shaft 26 which is journaled in collars 27 of a yoke 28. This yoke is in turn horizontally pivoted at 29 in bearings 30. A rigid arm 31 extends upwardly from 95 the yoke 28 and carries a toothed segment 32 which meshes with a pinion 33 upon the end of a shaft 34. The shaft 34 is supported in bearings 35, and pulleys 36, and 37 are loosely mounted thereon. Ratchet wheels 100 38 and 39 are fast upon this shaft, and pawls 40 and 41 carried by the pulleys 36 and 37 engage said ratchet wheels (see Figs. 12 and 14.)

A straight belt 42 leads from the pulley 105 37 to a pulley 43 of a countershaft 44, while a cross belt 45 leads from the pulley 36 to a pulley 46 upon said countershaft. The

countershaft is mounted in bearings 47 and carries a pulley 48. A belt 49 transmits movement from the countershaft 44 to a pulley 50 upon a power shaft 51. This power shaft preferably carries a balance wheel 52 and is mounted in bearings 53.

The operation of the device up to this point is as follows: The shore line is designated at A. The incoming wave not only 10 elevates the float, but tends to bodily wash it toward the shore, it being apparent from Fig. 9 that the chains possess sufficient slack to permit a limited movement of the float in any direction. It will therefore be apparent that two movements are imparted to 15 the power lever. An up and down movement, and an in-shore swinging movement.

The portion of the device heretofore described utilizes the vertical movement of the 20 float. During any horizontal or in-shore swinging movement of the float, the vertical shaft 26 merely turns in its bearings in the collars 27 and imparts no movement to the yoke 28, but any vertical movement of the 25 power lever rocks the yoke 28 upon its pivots 29 and imparts a swinging movement to the segment 32. This in turn, imparts oscillatory movement to the pinion 33 and to the shaft 34. This oscillatory movement of the 30 shaft by means of the connections described, imparts continuous rotary movement in one direction to the countershaft 44 and from said countershaft, to the power shaft 51. This part of the structure has been employed 35 in wave motors prior to this time and is well known to those skilled in the art. It consequently requires no further description.

The structure for utilizing the in-shore swinging movement of the float will now be 40 described.

The arm 25 of the power lever terminates in a horizontal shaft 54. This shaft is journaled in a yoke 55 and this yoke is in turn, mounted to swing upon vertical pivots 56 45 of a bearing 57. A rigid arm 58 extends from this yoke and swings bodily therewith. The outer end of this arm 58 passes through a sleeve 59 that is carried by a flexible member 60. This flexible member 60 forms part 50 of a belt 61 that passes over a pair of idler pulleys 62 (see Fig. 4) and also over a pulley 63 that is fast upon a shaft 64. Any vertical movement of the float merely rocks the horizontal shaft 54 in its bearings in the yoke 55, but any horizontal in-shore or off-shore 55 swinging movement of the float rocks the yoke 55 upon its pivots 56 and bodily swings the arm 58 to thereby impart a back and forth movement to the belt 61, and through 60 said belt imparts an oscillatory movement to the shaft 64. By means of pulleys 65, 66, 67, 68, ratchet wheels 69 fast upon the shaft 64, straight and cross belts 75 and 76 and pawls 70 carried by the pulleys 65, and 66, 65 the oscillatory movement of the shaft 64 is

converted into continuous rotation of the countershaft 44, and consequently into continuous rotation of the power shaft 51.

It will of course be understood that when the float seeks to return to its original position, the parts are moved in the reverse direction from that in which they move when the float is rising and moving toward the shore.

Guide members 71, carried by a bearing standard 72, serve to maintain the segment 32 in proper alignment with the pinion 33. The reason for providing the hinge closure 15 is to permit the rod 17 and lever 18 to be swung around upon the pier and entirely disengage it from the float in case a storm arises.

From the foregoing description, it will be seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claims.

Having described my invention, what I claim is:

1. In a wave motor, the combination with a power lever, of a float, a connection between said float and said power lever, a member pivoted to swing in a horizontal plane, a member pivoted to swing in a vertical plane, arms forming part of the power lever and pivotally connected to said members in such manner as to impart bodily movement to one of said members when said lever is moved in one direction, and to impart movement to the other of said members when said lever is moved in another direction, a driven shaft, and connections between said members and said driven shaft for converting the swinging movement of said members into continuous rotation of said shaft in one direction.

2. In a wave motor, the combination with a power lever, of a float, a connection between said float and said power lever, a member pivoted to swing in a horizontal plane, a member pivoted to swing in a vertical plane, arms forming part of the power lever and pivotally connected to said members in such manner as to impart bodily movement to one of said members only when said lever is moved in one direction, and to impart movement to the other of said members when said lever is moved in another direction, a driven shaft, and connections between said members and said driven shaft for converting the swinging movement of said members into continuous rotation of said shaft in one direction, said connections comprising a toothed segment carried by

one of said swinging members, a pinion in which said segment meshes, a shaft upon which said pinion is mounted, and connections between said shaft and the power 5 shaft.

3. In a wave motor, the combination with a float, of a housing thereon, a spider in said housing, anti-friction members carried by said spider and bearing against the sides 10 of said housing, a rod carried by said spider, and a power lever with which said rod is slidably engaged.

4. In a wave motor, the combination with a float, of a housing thereon, a spider in 15 said housing, anti-friction members carried by said spider and bearing against the sides of said housing, a rod carried by said spider, a power lever with which said rod is slidably engaged, and means for limiting the 20 outward movement of said rod with relation to said lever.

5. In a wave motor, the combination with a float, of a housing thereon, a spider in said housing, anti-friction members carried 25 by said spider and bearing against the sides of said housing, a rod carried by said spider, a power lever with which said rod is slidably engaged, a pair of arms rigid with the power lever, one of said arms terminating 30 in a vertical shaft and the other of said arms terminating in a horizontal shaft, a horizontally pivoted yoke in which the vertical shaft is pivotally mounted, a vertically pivoted yoke in which the horizontal 35 shaft is pivotally mounted, a power shaft, and connections between said yokes for converting the movement of said yokes into continuous rotation of said power shaft in one direction.

40 6. In a wave motor, the combination with a float, of a housing thereon, a spider in said housing, anti-friction members carried by said spider and bearing against the sides of said housing, a rod carried by said spider, a power lever with which said rod is slidably engaged, a pair of arms rigid with the power lever, one of said arms terminating 45 in a vertical shaft and the other of said arms terminating in a horizontal shaft, a 50 horizontally pivoted yoke in which the vertical shaft is pivotally mounted, a vertically pivoted yoke in which the horizontal shaft is pivotally mounted, a power shaft, and connections between said yokes for converting the movement of said yokes into con-

tinuous rotation of said power shaft in one direction, said connections comprising in part, a horizontally swinging arm rigid with the vertically pivoted yoke, a belt member with which the end of said arm 60 engages, pulleys over which said belt member passes, a shaft upon which one of said pulleys is mounted, and connections between said shaft and the power shaft.

7. In a wave motor, the combination with a float, of a housing thereon, a spider in 65 said housing, anti-friction members carried by said spider and bearing against the sides of said housing, a rod carried by said spider, a power lever with which said rod is slidably engaged, means for limiting the outward movement of said rod with relation to 70 said lever, and a removable closure for one side of said housing.

8. In a wave motor, the combination with a float, of a housing thereon, a spider in 75 said housing, anti-friction members carried by said spider and bearing against the sides of said housing, a rod carried by said spider, a power lever with which said rod is slidably engaged, a pair of arms rigid with the power lever, one of said arms terminating 80 in a vertical shaft and the other of said arms terminating in a horizontal shaft, a horizontally pivoted yoke in which the vertical shaft is pivotally mounted, a vertically pivoted yoke in which the horizontal shaft is pivotally mounted, a power shaft, connections between said yokes for converting 85 the movement of said yokes into continuous rotation of said power shaft in one direction, said connections comprising in part, a horizontally swinging arm rigid with the vertically pivoted yoke, a belt member with 90 which the end of said arm engages, pulleys over which said belt member passes, a shaft upon which one of said pulleys is mounted, and connections between said shaft and the power shaft, a toothed segment rigid with the horizontally pivoted yoke, a pinion with 95 which said segment meshes, a shaft upon which said pinion is fixed, and connections between said last named shaft and the power shaft.

In testimony whereof I affix my signature 105 in presence of two witnesses.

DAISY M. BARTEAU.
